CLAIM

The ornamental design for a container for chemical compounds that delay the ripening of fruits and vegetables, as shown and described.

DESCRIPTION

FIG. 1 is a front perspective view of a container for chemical compounds that delay the ripening of fruits and vegetables showing my new design;

FIG. 2 is a top plan view thereof;

FIG. 3 is a right side elevational view thereof;

FIG. 4 is a rear elevational view thereof;

FIG. 5 is a bottom plan view thereof; and,

FIG. 6 is a front elevational view thereof.
